Primary Examiner — Robert M Spear*Assistant Examiner* — Darcey E Heflin(74) *Attorney, Agent, or Firm* — Oblon, McClelland, Maier & Neustadt, L.L.P.(57) **CLAIM**

The ornamental design for a fluid dispensing adaptor for container, as shown and described.

DESCRIPTION

FIG. 1 is a top, front perspective view of a fluid dispensing adaptor for container according to our design;

FIG. 2 is a bottom, front perspective view thereof;

FIG. 3 is a front elevational view thereof;

FIG. 4 is a left side elevational view thereof;

FIG. 5 is a right side elevational view thereof;

FIG. 6 is a top plan view thereof; and,

FIG. 7 is a bottom plan view thereof;

The dashed lines in the drawings depict environmental subject matter only and form no part of the claimed design.

The dash-dot-dash lines in FIG. 7 form boundary portions and form no part of the claimed design.

1 Claim, 3 Drawing Sheets
